UNITED STATES PATENT OFFICE.

HENRY MUELLER, OF PITTSBURGH, PENNSYLVANIA, ASSIGNOR TO UNITED ENGINEERING & FOUNDRY CO., OF PITTSBURGH, PENNSYLVANIA, A CORPORATION OF PENNSYLVANIA.

ROTARY FEED MEMBER.

Original application filed January 26, 1923, Serial No. 614,961. Divided and this application filed March 18, 1924. Serial No. 700,125.

To all whom it may concern:

Be it known that I, HENRY MUELLER, a citizen of the United States, residing at Pittsburgh, county of Allegheny, and State of Pennsylvania, have invented a new and useful Improvement in Rotary Feed Members, of which the following is a full, clear, and exact description.

The present invention relates, broadly, to 10 the art of pulverized fuel feed, and more particularly to rotary feed regulators for fuel feeding apparatus, this application being a division of my co-pending application, Serial No. 614,961, filed January 26, 15 1923.

It has heretofore been proposed to feed pulverized fuel by means of a single screw-conveyor. The difficulty with such constructions has been the lack of uniformity 20 of feed and the tendency of the fuel to continue to flow after the conveyor was stopped, due to the fact that the single screw-conveyor offered a continuous passage for the finely divided fuel. This tendency of the 25 fuel to feed unevenly and to continue to flow after the stoppage of the conveyor often produced what is known in the art as "flushing". To overcome this disadvantage of the single screw-conveyor, it has been 30 proposed to provide a pair of cooperating screws. This type of feeder, however, has been found in actual practice to offer numerous disadvantages, such as rapid wearing of the parts, due to the constant grinding 35 action of one screw upon the other, and relatively large power consumption, due to the necessity for rotating the screws at a relatively high speed while overcoming a large amount of frictional resistance.

40 By the present invention the above mentioned and other disadvantages of the prior art constructions are overcome, an important object of the invention being to provide a fuel feeding system having a single rotating feeding member provided with peripheral fuel receiving means adapted to continuously and uniformly receive and discharge fuel with no tendency to "flushing".

45 A further object of the invention is to provide a construction in which the fuel feeding member may be rotated at slow

speed and with relatively small power consumption.

Another object of the invention is the provision of self-cleaning bearings for the 55 ends of the rotating feeding member adapted to prevent rapid wear.

Further objects and advantages of the invention will be apparent as the description proceeds.

60 The invention is illustrated in the accompanying drawings, in which:—

Figure 1 is a view showing my improved fuel feeding apparatus in elevation, a portion of the furnace being shown in section. 65

Figure 2 is a vertical sectional view of the 70 rotating feeding member and of the means for conveying the fuel to and from said member, and also showing the driving connections for said member.

Figure 3 is a sectional view taken on the line III—III of Figure 2 and looking towards the right.

Figure 4 is a plan view of the rotatable 75 feeding drum.

Figure 5 is a fragmentary sectional view showing the flexible connection between the auxiliary and main air conduits.

Figure 6 is a detail view of the flexible 80 diaphragm forming part of the connection shown in Figure 5.

Referring to the drawings, 1 indicates a housing or casing having a hopper 2 connected with a fuel feeding chute 3. Journaled in suitable bearings in the casing 1 85 is a shaft 4 upon which is mounted a drum 5. The drum 5 is fixed to the shaft 4 by means of an integral projection 6 on the drum cooperating with a cut-away or facetted portion 7 of the shaft, so that the drum 90 and shaft are affixed to each other against either relative rotational or longitudinal movement.

The ends of the drum 5 cooperate with 95 bearings 8 formed integral with the lower end of the hopper 2, and in order to counteract the tendency of the pulverized material which works in between the ends of the drum and its bearings to grind away the bearings and ends of the drum, the latter are each 100 provided with a plurality of independent peripheral grooves 9. Each bearing 8 en-

gages only a portion of the periphery of the corresponding end of the drum, the construction being such that any of the pulverized fuel which finds its way into the 5 grooves 9 at the upper side of the drum will simply be carried around in the rotation of the drum and escape at the discharge side of the drum. In this manner the grinding action of said material upon the bearings 10 and ends of the drum is reduced to a minimum.

The drum 5, instead of being provided with a single continuous groove, as in the ordinary screw-conveyor, is provided in its 15 peripheral surface with a series of independent grooves 10 which extend longitudinally of the drum, but in a direction diagonal to its axis. It will be seen that, with this construction, as the drum rotates, each independent groove 10 will be gradually filled from end to end with material from the hopper, and then, in the further rotation of the drum, will gradually empty its load at the discharge side of the drum, whereas, if the 20 grooves were arranged parallel to the axis of the drum, each groove would be filled simultaneously from end to end with material from the hopper and would discharge its entire load at substantially the same instant. 25 The present construction, therefore, insures a substantially uniform feeding of the material from the hopper into the air line and obviates any danger of "flushing." Moreover, the provision of the independent diagonally arranged grooves prevents "flushing" when the rotation of the drum is stopped.

Owing to the relatively large peripheral area of the feeding drum with its series of 40 independent grooves, the said drum can be rotated at a comparatively low speed, thereby enabling a small power consumption. For driving the drum, a small electric motor 45 is provided, which is attached to one end of the casing 1, as indicated in Figure 2, and drives the drum through the pinion 12, gear 13, pinion 14 and gear 15.

The main air supply conduit is represented by the reference numeral 16. The 50 conduit 16 communicates at its lower end with a hollow coupling member 17. A burner 18 is connected at one end to an end of the coupling member 17, and at its other end projects into the opening 19 in a wall 55 of the furnace 20.

Branching off from the main conduit 16 at the point 21 is an auxiliary air conduit 22. This auxiliary air conduit 22 includes a section 23 of the housing 1 arranged to 60 carry the auxiliary air supply past and in contact with the discharge side of the rotatable drum 5 and in a direction parallel to the axis of the drum. The section 23 is provided with a cleaning opening closed by a screw 65 plug 24. A suitable valve 25 is provided in

the conduit 22 for regulating the auxiliary air supply.

The section 23 has formed at one end thereof an integral flange 26, and clamped between this flange 26 and a ring 27 by means of bolts 28 is an annular metal diaphragm 29. The peripheral edge portion of the diaphragm 29 is clamped between a flange 30 formed integral with one end of the coupling member 17 and a ring 31 secured to the flange 30 by bolts 32, a packing member 33 being interposed between the ring 31 and diaphragm 29. Threadedly connected at one end to the ring 27 and projecting into the coupling member 17 is a pipe 34 forming an extension of the conduit 22. The construction just described provides a flexible and adjustable connection between the main air conduit and the discharge end of the auxiliary air conduit, so as to take care of any slight inaccuracies of alignment between the fuel feeding apparatus and the furnace. When it is desired to adjust the discharge end of the auxiliary conduit with respect to the main air conduit, this can be done by 80 loosening the nuts on the bolts 32 so as to permit shifting of the diaphragm 29 in its own plane, after which the nuts will be tightened again.

In the operation of the apparatus, the individual grooves 10 in the rotating drum are gradually filled with material from the hopper and gradually discharge this material into the auxiliary air conduit at the discharge side of the drum. The grooves, in the construction shown, extend the full length of the drum but only extend circumferentially of the drum through a relatively small arc, namely, less than 90°. Since the auxiliary air supply sweeps past the drum in a direction substantially parallel to the length of the grooves, the tendency of the auxiliary air supply is to clean the grooves of fuel and supply them with air, which is carried around in the grooves to aerate the fuel in the hopper. By reason of the fact that the discharge end of the auxiliary conduit 22 projects into the coupling member 17, the main air supply has an ejector action 105 upon the auxiliary air supply and the fuel carried in suspension therein, thereby further insuring against "flushing." The grooves 9 in the end portions of the drum prevent pulverized material which may work in between the end portions of the drum and its bearings from grinding away the bearings and the end portions of the drum.

I claim:

1. In apparatus for feeding pulverized fuel, a rotatable feeding member, means for supplying fuel to said member, and bearings for the end portions of said members, said bearings engaging said end portions throughout a portion only of the peripheral surfaces of the latter, said end portions each being 115 120 125 130

formed with a circumferential groove therein, said grooves being adapted to receive pulverized fuel working in between the end portions of the member and the bearings and to discharge such fuel at the discharge side of the member, substantially as described.

2. In apparatus for feeding pulverized fuel, a rotatable feeding member, means for supplying fuel to said member, and bearings for the end portions of said member, said bearings engaging said end portions throughout a portion only of the peripheral surfaces of the latter, said end portions each being provided with a plurality of circumferential grooves therein, said grooves being adapted to receive pulverized fuel working in between the end portions of the member and the bearings and to discharge such fuel at the discharge side of the member, substantially as described.

3. As an article of manufacture, a fuel feeding drum having a plurality of independent peripheral fuel receiving recesses extending longitudinally and circumferentially thereof, and bearing portions at the ends of said drum, said bearing portions having fuel conducting recesses therein out of communication with said fuel receiving

recesses and confined to said bearing portions, substantially as described.

4. As an article of manufacture, a fuel feeding drum having a plurality of independent peripheral fuel receiving recesses extending longitudinally and circumferentially thereof, and bearing portions at the ends of said drum, said bearing portions having fuel conducting recesses therein extending circumferentially thereof, and confined to said bearing portions, substantially as described.

5. In apparatus for feeding pulverized fuel, a rotatable feeding member having a plurality of independent peripheral fuel receiving grooves each extending substantially the full length of the drum and circumferentially thereof less than 180°, means for supplying fuel to said member, and bearings for the end portions of said member beyond the ends of the fuel receiving grooves, said end portions having peripheral fuel conducting recesses confined to said bearings but substantially unobstructed thereby, substantially as described.

In testimony whereof I have hereunto set my hand.

HENRY MUELLER.
